ATTORNEY

UNITED STATES PATENT OFFICE.

HUGH B. FRY, OF BATESVILLE, ARKANSAS.

COTTON-CULTIVATOR.

SPECIFICATION forming part of Letters Patent No. 281,259, dated July 17, 1883.

Application filed January 26, 1883. (No model.)

To all whom it may concern:

Be it known that I, HUGH B. FRY, a citizen of the United States, residing at Batesville, in the county of Independence and State of Arkansas, have invented certain new and useful Improvements in Cotton-Cultivators, of which the following is a specification, reference being had therein to the accompanying drawings.

My invention relates to cotton choppers and cultivators; and it consists in certain details of construction and arrangement of the several parts, as will be hereinafter more fully described in the specification, and pointed out in the accompanying drawings, in which—

15 Figure 1 is a plan view of my device; Fig. 2, a side elevation of same, and Fig. 3 a detail perspective view of the grooved drum or cylinder which actuates the chopping-lever.

Referring more particularly to the drawings, A represents the beams or main frame of the device, and B the drive-wheels which turn the shaft C, which is supported by suitable bearings on the beams A. Loosely mounted on the shaft C is a drum or cylindrical piece, M, having an eccentric groove, O, cut therein to receive a stud, P, on the under side of the lever F. This lever F is pivotally secured at one end to the cross-bar E, journaled in bearings e on the beams A. The free end 25 of the lever F is slotted to receive a bar, G, provided with a chopping-blade, G', said bar being attached to the lever F by a bolt, g'.

Pivotally attached to one of the handles D (preferably the right-hand one) is a lever, g, having pivotally secured to it a rod, Q, the lower end of which enters an opening in the arm R, attached to the pivoted cross-bar E.

One or more cultivator blades or shares, H, may be attached to the frame-pieces A at suitable points for the purpose. At the front end of the beams A a metal plate, K, receives said ends and is perforated to receive the standard i of the guide-rollers or wheels I and the draft means. The shaft C has a ratchet, a, at one side of the drum M, the drum being provided on this side with a pawl and spring, b c. By this means when the cultivator is moved forward the pawl engages with the ratchet and compels the drum to turn with

the shaft C. When the cultivator is moved backward, this engagement does not take place, and the drum and therefore the lever F are not actuated.

The bar G can be adjusted in the slot at the end of the lever F, so as to bring the chopping-blade near to or far away from the ground, as the necessity of the case may require.

In operation, the stud P is normally in the groove O. As the machine moves forward over the ground, the shaft C imparts motion to the grooved drum M, and this in turn imparts (through the intervention of stud P) a reciprocating motion to the bar F and chopper. If at any time it is desired to stop the chopping, as in thin cotton, or in ground in which there are stones, roots, stumps, &c., it is only necessary to press back the lever g, which turns back the arm R, and this arm turns the cross-bar E and raises the lever F and stud P from engagement with the groove O. By releasing the lever g this engagement is again made.

At a suitable point forward of the shaft C is a cross-bar, S, which supports the lever F, and which acts as a guide for the lever in its traverse movement.

The groove O can be so cut as to make the lever F and chopping-blade travel back and forth in intervals necessary to form an ordinary "stand of cotton."

The roller-standard i, which passes through openings in the plate K, is held in place by an upper and lower nut, so that the front end of the beams can be raised or lowered, as required. This plate K is preferably slotted or open across its rear end, where the front ends of the beams are inserted, so that said beams may be placed nearer together or farther apart and be held in place by suitable set-screws or bolts.

Having thus described my invention, what I claim is—

1. The combination, in a cotton-chopper and cultivator, of the adjustable beam, the actuating-shaft, a grooved drum loosely mounted on said shaft, a chopping-lever pivotally secured to a cross-bar journaled to the beams, with a lever pivotally secured to one of the handles, and connected by means of a rod and arm to

said cross-bar, substantially as shown, and for the purpose set forth.

2. In a cotton chopper and cultivator, the combination, with the beams and actuating mechanism, of the grooved drum M, lever F, pivoted cross-bar E, and lever g, connected to said bar E by rod q and arm R, as and for the purpose set forth.

In testimony whereof I affix my signature in presence of two witnesses.

HUGH B. FRY.
